(57) **CLAIM**

The ornamental design for an inviolate box, as shown and described.

DESCRIPTION

FIG. 1 is a top, front, left-side perspective view of an inviolate box showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof at a reduced scale, the bottom plan view being a mirror image;

FIG. 7 is a cross-section view thereof taken along line 7-7 of FIG. 2;

FIG. 8 is a cross-section view thereof taken along line 8-8 of FIG. 2;

FIG. 9 is an exploded view of the inviolate box of FIG. 1, showing the outer box component separated from the inner box component;

FIG. 10 is a top, front left side perspective view of the inner box component shown separately to reveal aspects of the design that may not be visible in other figures;

FIG. 11 is a front elevation view thereof;

FIG. 12 is a rear elevation view thereof;

FIG. 13 is a left side elevation thereof;

FIG. 14 is a right side elevation view thereof;

FIG. 15 is a top plan view thereof, at a reduced scale; and,

FIG. 16 is a bottom plan view thereof, at a reduced scale. In the drawings, the broken lines are for the purpose of illustrating environment only, and form no part of the claimed design.
